UNITED STATES PATENT OFFICE.

ARSÈNE SAULNIER, OF WALTHAM, MASSACHUSETTS, ASSIGNOR, BY MESNE ASSIGNMENTS, TO DRAPER CORPORATION, OF HOPEDALE, MASSACHUSETTS, A CORPORATION OF MAINE.

WARPING-MACHINE.

1,254,541.

Specification of Letters Patent. Patented Jan. 22, 1918.

Application filed June 21, 1915. Serial No. 35,241.

To all whom it may concern:

Be it known that I, ARSÈNE SAULNIER, a citizen of the United States, residing at Waltham, in the county of Middlesex, State 5 of Massachusetts, have invented a certain new and useful Improvement in Warping-Machines, of which the following is a specification, reference being had therein to the accompanying drawings.

10 The invention provides means for enabling the attendant upon a warping machine to distinguish between a stoppage of the winding operation due to the action of the stop-motion devices which are employed 15 for detecting breaking or failure of the individual warp-yarns, and a stoppage due to the action of the measuring devices. It provides means for preventing the attendant from inadvertently restarting the winding operation in case such operation has been arrested through the action of the measuring devices. This means comprises an automatic lock for the shipper devices by which the 20 said devices are locked automatically in unshipped condition after being tripped through the action of the measuring means, 25 but which leaves the shipper devices unlocked and capable of being operated to re-ship the driving connections into action in case the stoppage of the machine was due 30 to the action of the stop-motion devices employed for detecting breaking or failure of warp-yarns.

An illustrative embodiment of the invention is shown in the drawings, in which latter—

Figure 1 is a partly-sectional side elevation of a portion of a warping machine having the said embodiment applied thereto, the 40 driving power being on.

Fig. 2 is a similar view showing the shipper devices in unshipped and locked condition.

Fig. 3, Sheet 1, is a view of the lock, etc., 45 looking from the right hand side in Fig. 1.

Fig. 4, Sheet 2, is a similar view looking from the right hand side in Fig. 2.

Fig. 5, Sheet 1, is a partly sectional plan view of the lock.

50 Fig. 6, Sheet 3, is a side elevation of the clock and lock of the preceding figures.

Fig. 7 is an elevation thereof from the right hand side in Fig. 6, and Fig. 8 is a plan view thereof.

Fig. 9 is a side elevation of certain parts 55 of the warping machine, including the yarn-stop-motion but omitting the measuring roll and most of the gearing of the clock.

Having reference to the drawings,—

One side-frame 1 of a warping machine is 60 shown in Figs. 1 and 2, and in connection therewith are shown measuring, stopping, and shipper-devices of well-known construction and arrangement, and in addition the 65 illustrative embodiment aforesaid of the invention. The said measuring devices comprise the measuring roll 2 which is rotated through the contact of the traveling yarns with its periphery, the notched hub or scroll 10, and the motion-transmitting connections 70 by which the rotation of measuring roll 2 serves to cause the notched hub or scroll to rotate. The said connections comprise the worm 4 on one journal, 3, of the measuring roll, the worm-wheel 5 engaged by the said 75 worm and fast on the one end of a short shaft 6 supported in bearing 7, the worm 8 on the other end of such short shaft, and the worm-wheel 9 fast with the notched hub or scroll and engaged by the said worm. The 80 hub or scroll and the worm-wheel 9 are supported by a stud 11 upon which they are adapted to rotate. One element of the said stopping devices consists of the indicating lever 12, mounted pivotally upon a long stud 85 13 standing out from the side-frame 1. The said indicating lever is controlled in usual manner by the hub or scroll 10. Thus, one arm of the said lever is overweighted so as to cause, as usual, a lug 12^a that projects 90 from the said arm to bear against the periphery of the notched hub or scroll 10, and to enter a notch when the latter is presented to the lug by the rotation of the hub or scroll. The lever 12 is, in practice, so related 95 to the vibrator or feeler 23, 23 of the devices employed to stop the machine when a yarn breaks or runs out that so long as the overweighted arm is supported by the periphery of the hub or scroll its other arm is clear 100 of the vibrator or feeler, but when a notch in the hub or scroll is presented in position to receive the lug 12^a the movement of the lever which carries said lug into such notch swings its other arm into position to obstruct the vibrator or feeler. In Fig. 9 the overweighted arm is supported by the periphery of the hub or scroll, as just men-

tioned, but in practice it is supported by a 105 spring, the other end of which is supported by the periphery of the hub or scroll.

tioned, and the other arm, which has an upwardly facing hooked end, is held thereby below the path of movement of a lateral projection on an arm 24 that is fixed upon the 5 rockshaft 25 of the vibrator or feeler. Consequently, the vibrator or feeler is permitted to vibrate or swing unobstructedly. When a notch in the hub or scroll is presented in position as just mentioned so that the lever 10 12 is permitted to turn, the said hooked end is raised so as to intersect the said path of movement. The resulting engagement of the arm 24 of the vibrator or feeler with the obstructing arm of the indicating lever 12 15 results in the actuation of intermediate devices and the tripping of the shipper-devices and unshipping of the driving mechanism of the machine. The yarn-stop-motion with its vibrator or feeler and tripping devices 20 are not shown in Figs. 1 to 8. Various constructions thereof are well-known in the art, and those with which the invention is combined in practice may be of any convenient and approved character and construction. 25 In Fig. 9 the bars 23, 23, of the vibrator or feeler there shown are arranged to coöperate in usual manner with swinging drop-wires 26, 26, mounted pivotally in connection with supports 27, 27, and in practice 30 hung upon the respective yarns that are being wound in the machine. The required vibratory movement is communicated to the vibrator or feeler by means of a rotating grooved cam 28, a lever 29 that is engaged and actuated by the said cam, and give-away connections between the said lever and an arm 25^a that is fixed upon the rockshaft 25 of the vibrator or feeler. The said give-away connections comprise in this instance 35 a bar 30 that is connected pivotally by its lower end to the lever 29, and a second bar 31 that is connected pivotally by its upper end to the arm 25^a, the said bars being engaged with each other. The two bars are 40 overlapped with each other and the head of the bar 30 occupies a depression formed in one side face of the bar 31 between a square shoulder 31^a and a beveled shoulder 31^b, the end of the said head being squared 45 off for engagement with the said square shoulder 31^a and the head being also formed with a beveled shoulder to fit the beveled shoulder 31^b. The head of the bar 30 is retained normally in the said depression by 50 the tension of an expanding spiral spring 32 surrounding a pin 33 projecting from the bar 31 through a longitudinal slot 34 in the head of the bar 30, the said spring being confined and compressed between the head of 55 the bar 30 and a shoulder or head on the pin 33. The two bars pass through a guide 60 that is fixedly attached to the machine-frame 1, the said guide being located below the head of the bar 30. At the back of the 65 bar 30 it is furnished with a shoulder 30^a for

co-action with the outstanding toe of a tripping lever 36 which is pivoted to the machine-frame 1. In the operation of the machine, as the rotating cam 28 moves the lever 29 and bar 30 upward the head of the said 70 bar acts against the square shoulder 31^a of the bar 31 so that movement is transmitted to the bar 31 and arm 25^a to the vibrator or feeler, swinging the bars 23, 23, of the latter toward the right in Fig. 9. As the 75 lever 29 and bar 30 are moved downward by the action of the cam, the bar 31 and arm 25^a are moved in the same direction, partly by gravity and partly as a result of the engagement of the beveled shoulders with each 80 other, and thereby the vibrator or feeler is swung with yielding force toward the drop-wires 26, 26. In case the movement of the vibrator or feeler toward the drop-wires should be arrested by a dropped drop-wire the arm 25^a and bar 31 will be arrested in their downward movement and bar 30 85 will slip upon bar 31. Normally the shoulder 30^a of the bar 30 passes down at one side of the toe of the tripping lever 36, but 90 when the bar 31 is held from movement downward so that the bar 30 slips thereon the movement of one beveled shoulder upon the other spreads the two bars apart. Bar 31 rests against one side of the fixed guide 95 35. Consequently as the two bars are forced apart by the interaction of the beveled shoulders the bar 30 is shifted over toward the tripping lever 36 so that in the continued downward movement of the bar 30 its shoulder 30^a engages with the toe of the tripping-lever 36 and actuates the said tripping-lever to call the shipper-devices into action to bring about the unshipping of the driving power of the machine. When, subsequently, 100 the lever 29 and bar 30 are moved upward the said bar slips upward upon the bar 31 until the head of bar 30 reenters the depression in the bar 31, after which the two bars move in unison in actuating the vibrator 105 or feeler. Certain of the parts of the shipper-devices with which the features of the invention are connected in operation are shown. They are in this instance of a construction and arrangement in common use, 110 although they may be of any other preferred construction, etc. The said shipper-devices include the usual shipper-rod or detent bar 14 having its upper end arranged to work in a slot 15 in a holding plate 16 projecting 115 outward from side-frame 1, the said upper end being shouldered at one side for engagement with the bottom of the said holding plate at one end of the slot 15. The lower end of the said shipper-rod or 120 detent-bar is shown as connected pivotally in usual manner with an arm 18 of a rock-shaft 19, the latter being mounted in bearings in the opposite side-frames and having 125 connected therewith an arm 20 on which 130

a weight 21 is mounted with capacity for adjustment toward or from the rock-shaft 19 to vary its effect, the said rock-shaft being provided with a treadle 22. In the 5 operation of the machine the driving power is shipped on at the will of the operator by pressure applied to the treadle 22 in manner to force said treadle down and thereby rock the rock-shaft 19. This action, in addition 10 to shipping on the driving power through the connected devices (not shown) employed in warping machines, moves the rod or bar 14 downward so that its shoulder engages under the holding plate 16 as in Fig. 1. So 15 long as such engagement continues the driving power is kept on. The depression of the treadle and rocking of the rockshaft for the purpose of shipping on the driving power also serve to raise the weight 21. Un- 20 shipping is brought about by moving the upper end of the shipper-rod or detent-bar 14 in the proper direction to disengage its shoulder from the holding plate 16, namely from right to left in Fig. 1, such disengagement rendering the shipper-rod free to move 25 upward and permitting the weight 21 to turn the rockshaft in the direction to effect the unshipping, the turning movement of the rockshaft acting to push the shipper-rod 30 or detent-bar upwardly into the position which it occupies in Fig. 2. As is well-known, this disengagement of the shoulder is effected in machines in actual use when the movement of the vibrator or feeler of 35 the yarn stop-motion devices is interfered with through the action of the said devices on failure of a yarn or through the action of the measuring devices.

The automatic lock by which according 40 to the present invention the shipper-devices of a warping machine are locked automatically in unshipped condition after being tripped through the action of the measuring means may be variously contrived, con- 45 structed, and arranged within the scope of the invention. In the present illustrative embodiment of the invention, I have pro- 50 vided a locking member *b* that is constituted by a spring-actuated bolt which is adapted to enter a hole *o* in shipper-rod or detent-bar 14 for the performance of its locking function. For convenience, the said bolt is arranged to coöperate with the upper por- 55 tion of the shipper-rod. It is mounted in bearings provided in upstanding ears or lugs *a*⁴, *a*⁵, upon a small stand *a* that is at- 60 tached to the side-frame 1 by means of bolts *a*², *a*³, engaging with downturned ears *a*', *a*', of said stand. The spring *c* which actu- 65 ates the bolt is an expanding spiral spring and surrounds the stem of the bolt between ear or lug *a*⁵ and a collar *d* made fast in adjustable position upon the said stem by means of a clamping screw *e*. The spring 70 acts with a tendency to push the bolt end- wise in the direction of the shipper-rod or 75 detent-bar. Normally, however, the bolt is latched in retracted position as in Fig. 1, so as not to interfere with the engagement of the detent-portion of the shipper-rod or 80 detent-bar with the portion of holding-plate 16 that is located at the right-hand side of slot 15. To provide for this latching of the bolt in retracted position so as to permit the said engagement to take place, the bolt 85 *b* is furnished with a downwardly-projecting finger *g*, and a latch *f* is provided in connection with stand *a* for coaction with such finger. Latch *f* in this instance is in the form of a bar or strip arranged at right 90 angles with relation to the bolt, and having in one end-portion thereof a hole which fits loosely the stem of a screw *h* applied to the stand *a* and projecting downward therefrom. The latch is kept pressed upward 95 into engaging position by means of an expanding spiral spring *i* mounted upon the stem of the screw, between the head of the screw and the under side of the latch *f*. The latch has capacity for vertical move- 100 ment or play between guides *k*, *k*, projecting downward from the under side of the stand *a*. Such guides hold the latch from movement transversely. The bolt is moved by hand toward the right into its position 105 shown in Fig. 1, by taking hold of a handle conveniently mounted upon the screw *e*, as shown, and forcing the bolt endwise in the direction from left to right in the said figure. To enable finger *g* to pass the latch 110 as as the bolt is being thus moved, the end of such finger is rounded or beveled off so that as it is carried against the latch it de- 115 presses the latter and then passes over it, the latch snapping up into place at the front 105 of the finger *g* as soon as such finger passes the latch. In its latched position the bolt is held withdrawn from the shipper-rod or 120 detent bar so as to leave the latter free to be depressed and also free to be swung into 110 position for its detent-shoulder to engage with the holding-down portion of holding-plate 16, as in Fig. 1. When the shipper-rod or detent bar is thus engaged with the holding-plate, its hole *o* is below the bolt 115 and a solid portion of the shipper-rod or detent bar is presented in line with the act- 125 ing end of the bolt *b*. The shipper-rod or detent bar occupies a hole *a*³ in stand *a* of size suitable to permit the required extent 120 of lateral play of the shipper-rod or detent bar in being moved into engagement with one side of holding-plate 16 and being dis- 130 engaged therefrom.

The yarn-stop-motion acts in well-known manner in case of failure or breakage of a 125 yarn to dislodge shipper-rod or detent bar 14 from engagement with holding-plate 16, so as to render the shipper-rod or detent bar free to rise through the hole 15 in the hold-

ing-plate. In the case of the illustrated construction this is accomplished through the action of the tripping-lever 36. The latter has a lateral projection for engagement with the shipper-rod or detent-bar, and when the tripping-lever is actuated through the engagement therewith of the shoulder 30^a of the downwardly moving bar 30 the said projection moves the shipper-rod or detent-bar out of engagement with holding-plate 16. This dislodging of the shipper-rod or detent bar releases the shipper-devices and accordingly they act to unship the driving connections and so stop the 10 operation of the machine. This takes place without calling the bolt *b* into action. It will be observed that therefore when released by the action of the yarn-stop-motion devices in case of failure or breakage of a 15 yarn the shipper-devices are not locked by the lock *b*, and the driving connections can be shipped-on again at the will of the attendant merely by pressing down upon the treadle 22, thereby restarting the machine. 20 The freedom of the treadle to be depressed will indicate to the attendant the fact that the stoppage was due to yarn failure or breakage.

For the purpose of automatically locking 30 the shipper-devices in unshipped condition when the machine is stopped automatically under the dictation of the measuring devices, I combine the bolt *b* operatively with the latter devices. This is accomplished in 35 the present instance by furnishing indicating lever 12 with a tripping finger *m*. The latter is arranged so that while lug 12^a is engaged by the periphery of hub or scroll 10 and the lever is held thereby in inoperative 40 position, the finger *m* is kept retracted from latch *f* and entirely clear of the same, as in Figs. 1 and 3, but also so that when a notch of hub or scroll 10 is presented in 45 position to be entered by the lug the resulting movement of the indicating lever 12, in addition to calling the yarn-stop-motion mechanism into play to dislodge the shipper-rod or detent bar from the holding-plate, will carry finger *m* against latch *f* so as to 50 unlatch the bolt and permit it to be moved endwise by its spring *c*. The rising of the shipper-rod or detent bar as soon as dislodged will carry the hole *o* into line with the acting end of bolt *b*, and as soon as such 55 hole and acting end register with each other the now unlatched bolt will enter the hole. See Fig. 2. The shipper-devices will be locked thereby in unshipped condition, and cannot be operated by the attendant to re- 60 start the machine until after the bolt has been withdrawn from hole *o* and thereby disengaged from the shipper-rod or detent bar. Consequently an attempt of the attendant to restart the machine by pressing down 65 upon the treadle 22 will fail. The inability

to move the shipping devices to restart the machine will render apparent the fact that the stoppage was due to the automatic action of the measuring devices and not due to detection of breakage or failure of a yarn. 70

The spring *c* may be of sufficiently strong tension to actuate bolt *b* to dislodge the shipper-rod or detent bar from holding engagement with the under-side of holding-plate 16 immediately upon the unlatching of 75 the said bolt, without depending upon the yarn-stop-motion devices being called into action through interaction of indicating lever 12 and the vibrator or feeler.

The hub or scroll 10 of the so-called 80 warper "clock," as herein described, may be constructed and combined so as to act simply to bring about the automatic stopping of the machine when the length of yarns required for a warp has been wound. In 85 such case the said hub or scroll may have only one notch. The drawings show a clock of the kind used in a lease-warper, that is to say designed to stop the machine automatically at intervals to permit leases to be 90 struck and successive sets of lease-threads to be introduced among the threads of a warp, and finally stop it when the entire required length of warp has been wound. For these purposes, the hub or scroll 10 has 95 formed in its periphery longitudinal grooves 10^a, 10^a equidistant from one another, and it also is formed with a deep radial notch 10^b at the end of one of the said grooves. The periphery of the hub or scroll is grooved 100 circumferentially, also, as shown in Figs. 7 and 8, to receive the end of the lug 12^a, the groove being formed spirally around the hub or scroll and terminating at the deep notch 10^b, so that in successive revolutions 105 of the hub the lever 12 will be caused to travel gradually to the outer end of the hub. To permit the lever to travel outward and subsequently be moved inward again to the desired starting position, its hub-portion or 110 sleeve is mounted upon a long pivotal stud 13 projecting from side-frame 1, with capacity to slide lengthwise of the latter. With this construction, as is well-known, the winding is started with the lug 12^a of the 115 lever 12 entered into the spiral groove at a distance inward from the outer end of the hub or scroll proportioned to the length of warp required, and each time that in the rotation of the hub or scroll a groove 10^a 120 is presented to the lug 12^a the indicating lever becomes effective to call a stoppage of the machine. This permits the attendant to strike the leases and introduce the leasing threads, the machine being restarted each 125 time and the winding proceeded with until the lug 12^a enters the final notch 10^b. The locking devices may be caused to lock the shipper-devices every time the lug 12^a enters a groove 10^a, as well as when it enters the 130

final notch, or the finger m may be adjusted upon the indicating lever so that the finger will not act upon the latch f when the lug 12^a enters one of the comparatively shallow grooves, and will act upon said latch only when the lug enters the deep notch 10^b at the end of the length required for the warp. The necessary adjustment may be provided for variously. In this instance the shank 10 or upper portion of the finger is formed with a longitudinal slot for the stem of the screw m^2 which attaches the finger to the indicating lever. This slot provides for adjustment of the finger either upward into 15 such a position thereon that its acting end will not disengage the latch when the lug 12^a enters a groove 10^a and will effect disengagement only when the said lug enters the final notch 10^b ; or downward into such 20 a position thereon that the finger will disengage the latch every time the lug 12^a enters a groove as well as when it enters the final notch.

When automatic stoppage takes place in 25 the case of an ordinary warping machine it is not always apparent to the attendant what has operated to occasion the stoppage. The stoppage may have been brought about by the action of the yarn-stop-motion, or it may 30 have been brought about by that of the clock. In the majority of cases it will be due to the operation of the yarn-stop-motion, and as this is expected by the attendant she ordinarily proceeds accordingly. That 35 is to say, she will look to ascertain if a thread has broken and will undertake to find and mend the same. Usually, in the endeavor to locate a broken thread, the attendant starts up the machine in order to 40 draw the threads forward so that she may catch sight of the broken end in case the breakage should have taken place between the warper and the creel. The restarting of the machine draws the broken end forward 45 into view. In case the machine has not been stopped by the yarn-stop-motion but by the action of the clock, this restarting not only entails a loss of time but it draws forward an excess quantity of yarn from the 50 creel and winds the same, thereby winding a length of warp exceeding the predetermined length. My invention obviates these drawbacks. When a warping machine is equipped with the invention, the attendant is at once 55 informed, in attempting to restart the machine following an automatic stoppage, whether such stoppage was brought about by the yarn-stop-motion or by the clock. If it was brought about by the yarn-stop-motion 60 she is able to actuate the shipper devices to restart the winding. If it is brought about by the clock, she finds the shipper mechanism locked and is unable to restart the machine. No time is lost in ascertaining 65 whether or not a yarn has broken or

failed, and there is no winding of an excess length.

I claim as my invention:—

1. In a warping-machine, in combination, a roll engaging with the yarns and having 70 combined therewith a device operated thereby for registering the length of yarns passing through the machine, means for occasioning stoppage by unshipping of the driving-power on passage of a predetermined length of yarns, the shipper-devices 75 for the driving mechanism of the machine controlled by such means, a yarn-stop-motion also controlling the said shipper-devices, and a lock by which the said shipper-devices 80 are locked automatically in unshipped condition when tripped through the action of the said means but left unlocked and capable of being operated to reship the driving connections into action when tripped on break- 85 age or failure of a yarn.

2. In a warping-machine, in combination, the shipper-devices of such machine, a yarn-stop-motion adapted to cause unshipping of the driving-power in case of yarn failure, a 90 shipper-lock, and devices for registering the length of yarn, arranged to act through the feeler connections of the yarn-stop-motion to cause unshipping when a predetermined length has been warped, and operatively 95 combined with the said shipper-lock to call the latter into action at such time to lock the shipper-devices with the driving-power unshipped.

3. In a warping-machine, in combination, 100 the shipper-devices of such machine, a yarn-stop-motion adapted to cause unshipping of the driving-power in case of yarn failure, a shipper-lock, and yarn measuring devices arranged to act through the feeler connections 105 of the yarn-stop-motion to occasion unshipping when a predetermined length of yarn has been warped, and operatively combined to call the said shipper-lock into action at such time to lock the shipper-devices with 110 the driving-power unshipped.

4. In a warping-machine, in combination, 115 the shipper-devices of such machine, a shipper-lock, a yarn-stop-motion adapted to cause unshipping of the driving-power in case of yarn failure, and yarn measuring devices including a roll engaging with the yarn in its passage and a lever that acts through the feeler connections of the yarn-stop-motion to occasion unshipping when a predetermined length of yarn has been warped and also acts to call said shipper-lock into action at such time to lock the shipper-devices with the driving-power unshipped.

5. In a warping-machine, the combination 125 with the clock-mechanism, the indicating member through which said mechanism brings about stoppage, and the manually-operated shipper-devices for the driving mechanism of the machine, of a locking de- 130

vice for locking said shipper-devices with the driving power unshipped called into operation through the said indicating member.

6. In a warping machine, the combination 5 with the clock mechanism and the manually-operated shipper devices for the driving mechanism of the machine, of a lock for the shipper devices and a latch controlled by said clock for holding the lock inoperative 10 during the regular working of the machine, whereby the lock is released to lock the shipper devices in unshipped position when said devices have been tripped by the clock.

7. In a warping machine, the combination 15 with the clock mechanism, the indicating lever, and the shipper devices, of a lock for the shipper devices holding the latter inoperative during the regular working of the machine and a latch for the lock controlled 20 by said indicating lever through adjustable means, whereby the operation of said latch by the clock may be varied, as and for the purposes described.

8. In a warping machine, the combination 25 with the clock mechanism and the shipper devices unshipping automatically when released, of an automatically actuated locking device retained in inoperative condition by means controlled by said clock mechanism 30 and adapted when released by said mechanism to move the shipper devices into position for unshipping and also to lock the same in unshipped position, as and for the purposes described.

35 9. In a warping machine, in combination, shipper-devices, clock mechanism, an indicating lever controlling the shipper-devices, a shipper-lock, and means intermediate the lever and the shipper-lock through which 40 the lever calls the shipper-lock into action, said means adjustable to render the shipper-lock idle.

10. In a warping machine, in combination, shipper-devices, an indicating lever 45 controlling the shipper-devices, clock mechanism constructed to produce movements of the indicating lever of different extents, and a shipper-lock adapted to be controlled by the indicating lever, called into action by 50 a movement of said lever of a given extent and left idle in case of a movement of less extent.

11. In a warping machine, in combination, shipper-devices, an indicating lever 55 controlling the shipper-devices, clock mechanism constructed to produce movements of the indicating lever of different extents, a shipper-lock, and a latch for the shipper-lock operated to free the latter in case of a 60 movement of given extent of the indicating lever and remaining in control thereof in case of a movement of less extent.

12. In a warping machine, in combination, the shipper-devices thereof, a yarn-stop- 65 motion adapted to occasion unshipping of

the driving-power in case of yarn-failure, yarn-measuring devices, including an actuating roll and a scroll that are rotated by the yarn in its passage and a scroll-lever that renders said yarn-stop-motion devices 70 effective to occasion unshipping when a predetermined length of yarn has passed, and a shipper-lock which also is called into action by the scroll-lever at such time to lock the shipper-devices with the driving-power un- 75 shipped.

13. In a warping machine, in combination, a yarn-stop-motion adapted to occasion unshipping of the driving-power in case of 80 yarn-failure, measuring devices including an actuating roll and a scroll that are rotated by the yarn in its passage and a scroll-lever that renders said yarn-stop-motion effective to occasion unshipping when a predetermined length of yarn has passed, the shipper-devices of said machine including a detent-bar, as 14, and means caused by the scroll-lever to engage with the said detent-bar to lock the shipper-devices with the driving-power unshipped. 90

14. In a warping machine, in combination, a yarn-stop motion adapted to occasion unshipping of the driving-power in case of yarn-failure, the shipper-devices of said machine including a detent-bar, as 14, a 95 shipper-lock adapted to engage with said detent-bar to lock the shipper-devices with the driving-power unshipped, a detent normally keeping said shipper-lock out of engagement with the detent-bar, and measuring devices including an actuating roll and a scroll that are rotated by the yarn in its passage and a scroll-lever that renders said yarn-stop-motion effective to occasion unshipping when a predetermined length of 100 yarn has passed and that also operates said detent to free the shipper-lock for engagement with said detent-bar to lock the shipper-devices with the driving-power unshipped. 105

15. In a warping machine, warp measuring mechanism, stop-motion mechanism comprising a longitudinally movable shipper rod having a shoulder, a plate engaging said shoulder to prevent unshipping movement of 110 said rod and thus maintain the stop-motion mechanism inoperative, a knock-off lever for said rod, a latch to engage said rod in and maintain it in unshipped position, and means made operative by the measuring mechanism upon the completion of a predetermined length of warp to actuate said knock-off lever and cause said latch to engage said rod. 115

16. In a warping machine comprising 125 warp measuring mechanism, warp-end absence or failure detecting mechanism, stop-motion mechanism actuated both by said measuring mechanism upon the completion of a predetermined length of warp and 130

by said detecting mechanism upon the absence or failure of a warp-end comprising a starting and stopping member, locking means coöperating with said member, and means actuated by the measuring mechanism upon its actuation of the stop-motion mechanism to cause the locking means to lock the starting and stopping member in inoperative position.

17. A warping machine comprising warp measuring mechanism, stop-motion mechanism actuated both by the measuring mechanism upon the completion of a predetermined length of warp and by the absence or failure of a warp end, means to lock the warping machine against restarting actuated by the measuring mechanism upon the completion of a predetermined length of warp, and means to prevent the warping machine from being so locked when the stop-motion mechanism is actuated by the absence or failure of a warp end, said means including an element controlled by the warp measuring mechanism.

18. In a warping machine, in combination, shipper-devices, clock mechanism, an indicating lever controlling the shipper devices, a shipper-lock, and means intermediate the lever and the shipper-lock through which the lever calls the shipper-lock into action.

19. In a warping machine, in combination, a yarn-stop-motion adapted to occasion un-

shipping of the driving power in case of yarn-failure, registering devices including a scroll and a scroll-lever that renders said yarn-stop-motion effective to occasion unshipping when a predetermined length of yarn has been registered, the shipper-devices of said machine including a detent-bar, as 14, and means caused by the scroll-lever to engage with the said detent-bar to lock the shipper-devices with the driving-power unshipped.

20. In a warping machine, in combination, a yarn-stop-motion adapted to occasion shipping of the driving-power in case of yarn-failure, the shipper-devices of said machine including a detent-bar, as 14, a shipper-lock adapted to engage with said detent-bar to lock the shipper-devices with the driving-power unshipped, a detent normally keeping said shipper-lock out of engagement with the detent-bar, and registering devices including a scroll and a scroll-lever that renders said yarn-stop-motion effective to occasion unshipping when a predetermined length of yarn has been registered and that also operates said detent to free the shipper-lock for engagement with said detent-bar to lock the shipper-devices with the driving-power unshipped.

In testimony whereof I affix my signature.

ARSÈNE SAULNIER.

Copies of this patent may be obtained for five cents each, by addressing the "Commissioner of Patents, Washington, D. C."

Corrections in Letters Patent No 1,254,541.

It is hereby certified that in Letters Patent No. 1,254,541, granted January 22, 1918, upon the application of Arsène Saulnier, of Waltham, Massachusetts, for an improvement in "Warping-Machines," errors appear in the printed specification requiring correction as follows: Page 6, claim 7, line 17, beginning with the word "holding" strike out all to and through the word "machine", line 19; same page and claim, line 19, after the word "lock" insert the words *holding the latter inoperative during the regular working of the machine and*; and that the said Letters Patent should be read with these corrections therein that the same may conform to the record of the case in the Patent Office.

Signed and sealed this 22d day of April, A. D., 1919.

[SEAL.]

F. W. H. CLAY,

Acting Commissioner of Patents.

Cl. 28—31.
